UNITED STATES PATENT OFFICE

LAURENCE M. PERSONS, OF ST. LOUIS, MISSOURI

FURNACE THERMOSTAT CONTROL

Application filed August 8, 1930. Serial No. 473,894.

My invention relates to improvements in control means for furnaces and the like. One object is the provision of thermostatic means, responsive to furnace temperature, for supplementing an ordinary thermostat for preventing overheating of a furnace. Other objects will appear from time to time in the course of the specification and claims.

I illustrate my invention more or less diagrammatically in the accompanying drawing, wherein:

Figure 1 is a side elevation with parts in section, and including a wiring diagram;

Figure 2 is a section on the line 2—2 of Figure 1;

Figure 3 is a section on the line 3—3 of Figure 2;

Figure 4 is a section on the line 4—4 of Figure 3; and

Figure 5 is a section on the line 5—5 of Figure 4.

Like parts are indicated by like symbols throughout the specification and drawing.

Referring to the drawing, A generally indicates a furnace or the like which may include the flue pipe A¹ and the hot air inlets A². A³ indicates a door for the furnace and A⁴ a draft door. A⁵ indicates a check draft door.

B diagrammatically indicates a draft control mechanism, the details of which form no part of the present invention, but which includes the lever arms B¹ and B². The lever arm B¹ is connected by the flexible connection B³ with the door A⁵. And the lever B² is connected by the flexible connection B⁴ with the door A⁴. B⁵ diagrammatically indicates a room thermostat as in circuit as by the conductive connections B⁶ with any suitable electric operating mechanism associated with the control means B. B⁷ indicates a transformer, and B⁸ conductive connections between the transformer and any suitable source of electric power. It will be understood that

in response to varying temperature conditions and to the actuation thereby of the thermostat B⁵, the lever arms B¹ and B² are actuated to control the doors A⁴ and A⁵. From the position in which they are shown in Figure 1, it will be understood that the check draft

door A⁵ is opened and the draft door A⁴ is closed, which position will be maintained until the room temperature falls to such a point as again to actuate the thermostat B⁵ and to cause a reversal of the positions of the two doors.

C diagrammatically indicates a supplemental thermostat member and its associated parts. It may include, for example, the base plate C¹ upon which is mounted a housing C² connected thereto as by the pins or connections C³. Positioned within the housing C² is the base C⁴ of insulating material. Pivoted for rotation in relation to the plates C¹ C² and the base C⁴ is the shaft or pin C⁵, the lower end of which penetrates in an aperture C⁶ in the plate C¹ and through the aperture C⁷ in the furnace wall. Downwardly extending from the plate C¹ is a pin C⁸. Secured at one end of the pin C⁸ and secured at the other to the pin or shaft C⁵ is a bimetallic coil C⁹. It will be understood that this coil flexes in response to changes of temperature to which it is subjected, thus causing rotation of the shaft or pin C⁵. The size of the aperture C⁷ is such that the member C⁹ may pass therethrough to permit easy installation and removal of the assembly herein described.

Rotatably positioned upon the base C⁴ is the arm D also of insulating material. The arm D is mounted concentrically for rotation with the pin C⁵, but is rotatable in relation thereto. The pin C⁵ is provided at its upper end with a head D¹ fixed against rotation in relation thereto. The head D¹ is provided with an upstanding lug D². Pivotally mounted on the upper end of the pin C⁵ is a yoke D³. Between the yoke D³ and the head D¹ is positioned a spring D⁴, one end of which engages the upstanding lug D². The tendency of this spring is to cause rotation of the yoke D³ in relation to the pin C⁵. D⁵ indicates an insulating plug associated with the yoke D³. To it is secured the conductive arm or leaf D⁶, one end of which is opposed to the permanent magnet D⁷ mounted upon the arm D. Associated with the permanent magnet is an adjustable contact element D⁸, which in turn is opposed

to a contact D^9 at the end of the leaf D^6 . D^{10} D^{11} are conductive connections for the contacts D^8 D^9 respectively, being independently between the circuit with the conductive connection B^6 between the room thermostat and the control mechanism B. D^{12} is any suitable calibration upon the base C^4 aligned with the indicating tip D^{13} of the arm D.

10 E indicates a cover for enclosing and protecting the mechanism upon the plate C^2 .

It will be realized that whereas I have described and shown a practical and operative device, that nevertheless many changes may 15 be made in size, shape, number and disposition of parts without departing from the spirit of my invention. I therefore wish my drawing to be taken as in a broad sense illustrative and diagrammatic, rather than 20 as limiting me to any precise showing herein, except so far as I limit myself specifically by the language of my claims.

The use and operation of my invention are as follows:

25 The supplemental thermostat control herein described is adapted to be associated directly with the furnace and includes a thermostat member, for example the bimetallic coil or strip C^9 , which is subjected more or 30 less directly to the heat of the furnace or of the hot water, steam or air delivered by the furnace or heater. The device is associated with the furnace or heater structure itself and serves to prevent overheating. As an example, if an oversize furnace or heating plant 35 is employed in a small house, my supplemental control prevents overheating of the furnace, even though the normal room temperature thermostat control B^5 may fail to function. A good example is where a window is 40 left open and blows cold air on a room thermostat, or that the room thermostat may call for heat and may make or break a heating circuit, even though the furnace is actually 45 overheated.

I illustrate the coil C^9 as positioned within the bonnet or top of a furnace with the switch mechanism on the outside and the bimetallic member positioned within the wall 50 of the furnace. The make and break mechanism of the switch, including the contacts D^8 and D^9 , is in series with the room thermostat. The shaft C^5 is adapted to be rotated by movement of the coil C^9 in response 55 to changes of the temperature to which the coil is subjected. Movement of the coil rotates the shaft C^5 in a given direction and may move the pin D^2 against the opposed stop portion D^{15} of the yoke D^3 , thereby rotating the movable switch leaf D^6 . This 60 switch leaf may normally be held with its contact D^9 opposed to the contact D^8 as by the action of the spring D^4 , and also by the action of the permanent magnet D^7 . The 65 purpose of the permanent magnet is to pro-

vide a quick break, the contact being normally urged against it by the side spring. The permanent magnet is mounted on the adjustable arm D and the opposed spring contact member D^6 is separately mounted on 70 the pivoted yoke D^3 . Thus rotation of the shaft C^5 moves the pin D^2 against spring pressure and breaks the contact in response to an increase in temperature. On the other hand, a decrease in temperature causes counter rotation of the shaft, but this counter rotation does no damage and merely rotates the pin D^2 out of contact with the opposed stop 75 leaving the contact D^9 spring thrust in contact with the permanent magnet and the electric contact D^8 . The calibration of the base C^4 serves as a dial, so that the normally fixed contact D^8 may be set at any desired position. Assuming that it is set at a predetermined position to actuate the device at a predetermined temperature, it is then not disturbed and the fixed contact D^8 remains constantly positioned. When the temperature within the furnace reaches a predetermined point, the bimetallic coil C^9 rotates the shaft C^5 and forces the contact D^9 away from the opposed contact D^8 . The permanent magnet provides the desired snap or quick action. When the circuit is broken between D^8 and D^9 , it breaks the connection between the room 90 thermostat B^5 , through the conductive connections B^6 to the actuating device C, and makes the actuating device B respond to the increase in temperature of the furnace regardless of what may be the indication of the room thermostat. Without going into details of the control mechanism B, it will be understood that when the circuit B^6 is broken, the lever arms B^1 and B^2 normally 95 are caused to take the position in which they are shown in Figure 1, closing the draft door A^4 and opening the check A^5 . It will be understood that while I have shown my invention as applying to a hot air furnace, it 100 may be used with other heaters, for example 105 with water vapor and steam heaters. 110

I claim:

1. A temperature responsive control element comprising a base plate, a plurality of studs secured to one face thereof, and extending therefrom, a switch supporting plate secured to the free ends of the studs, a switch member mounted on the switch supporting plate, temperature responsive means mounted on the opposite faces of the base plate, said base plate and switch supporting plate being provided with aligned apertures, and an operating connection between the temperature responsive means and said switch member extending through said apertures. 115

2. A temperature responsive control element comprising a base plate, a plurality of studs secured to one face thereof and extending therefrom, a switch supporting plate secured to the free ends of the studs in spaced 120 125 130

- relation to the base plate, a switch member mounted on the switch supporting plate, a stud member secured to the opposite face of the base plate, temperature responsive means 5 mounted upon said stud in spaced relation to the base plate, said base plate and switch supporting plate being provided with aligned apertures, and an operating connection between the temperature responsive 10 means and said switch member extending through said apertures.
3. A temperature responsive control element comprising a base plate, a switch member mounted in spaced relation to one face 15 of the base plate, said switch member including a stationary contact and a movable contact, means for relatively adjusting said contacts to vary the point at which they open and close, temperature responsive 20 means mounted on the opposite face of the base plate, and an operating connection between the temperature responsive means and the switch member, a lost motion connection between said connection and the movable 25 switch contact, and resilient means biasing the movable switch contact to closed position.

Signed at St. Louis, Missouri, this 4th day of August 1930.
